ANTENNA ROTATOR CONTROL HOUSING

Paul A. Dicke, New Bremen, Ohio, assignor to Crown
Controls Corporation, New Bremen, Ohio, a corpora-
tion of Ohio

Filed June 20, 1963, Ser. No. 75,440

Term of patent 14 years

(Cl. D26—14)

FIG. 1

FIG. 2

FIG. 3

FIG. 4

FIG. 5

FIG. 6

FIGURE 1 is a perspective view of an antenna rotator control housing made in accordance with this invention.
FIGURE 2 is a side elevational view of the housing.
FIGURE 3 is a front elevational view of the housing.
FIGURE 4 is a plan view of the housing.
FIGURE 5 is a rear elevational view of the housing.
FIGURE 6 is a perspective view of the rear of the housing.

The broken line showing is for illustrative purposes only.

I claim:

The ornamental design for an antenna rotator control housing, as shown and described.
